WATERPROOF CASE FOR A PHOTOGRAPHIC CAMERA

Nobuki Matsumoto, Sadao Okada, Masayuki Sakuma,
and Ohiko Yagi, Tokyo, Japan, assignors to Kabushiki-
Kaisha Ricoh, Tokyo, Japan

Filed Aug. 11, 1969, Ser. No. 18,635

Claims priority, application Japan Apr. 23, 1969

Term of patent 7 years

Int. Cl. D16—07

U.S. Cl. D61—1

FIG. 1

FIG. 2

FIG. 3

FIGURE 1 is a front, top and left side perspective view of a waterproof case for a photographic camera, showing our new design;

FIGURE 2 is a rear, top and right side perspective view; and

FIGURE 3 is a sectional view through a vertical plane passing through the nominal optical axis of the said waterproof case, shown in FIGURE 1.

Portions of the figures of the drawings are diagonally lined to indicate transparency.

We claim:

The ornamental design for a waterproof case for a photographic camera, substantially as shown and described.
